CLAIM

The ornamental design for a menstrual cramp relief device as shown and described.

DESCRIPTION

FIG. 1 is a perspective view of a menstrual cramp relief device;

FIG. 2 is a front elevational view of the menstrual cramp relief device of FIG. 1;

FIG. 3 is a back elevational view of the menstrual cramp relief device of FIG. 1;

FIG. 4 is a first side elevation view of the menstrual cramp relief device of FIG. 1;

FIG. 5 is a second side elevation view of the menstrual cramp relief device of FIG. 1;

FIG. 6 is a top plan view of the menstrual cramp relief device of FIG. 1; and,

FIG. 7 is a bottom plan view of the menstrual cramp relief device of FIG. 1.

The broken lines shown in the figures represent environment and are not included in the claimed design.

1 Claim, 7 Drawing Sheets
